UNITED STATES PATENT OFFICE

JOHN R. ELLIS, OF HOUSTON, TEXAS

TELEPHONE ATTACHMENT

Application filed January 6, 1930. Serial No. 418,705.

My invention relates to attachments for telephones and has particular reference to devices for holding the receiver of a telephone.

In the ordinary type of desk telephone it is necessary for the user of the telephone to raise the receiver from the hook or switch lever and hold it in one hand while he is talking into the transmitter. Sometimes it is very inconvenient to have to continually hold the receiver while the conversation over the telephone is proceeding. It is frequently necessary to write down matter connected with the telephone conversation and even when it is not necessary to use the hands for other purposes the continuous holding of the receiver is burdensome.

It is an object of my invention to provide an attachment for ordinary desk telephones whereby it becomes unnecessary for the user of the telephone to hold the receiver during the conversation.

I contemplate the provision of means to hold the receiver in the proper position adjacent the transmitter and to provide additional means for operating the switch lever whereby the hook or switch is operated to open or close the circuit.

I have as a further object the provision of a supporting device for the receiver which may be used with or without a latching means for the telephone hook. My device is also capable of convenient attachment to any ordinary type of desk telephone without modification thereof and in a minimum of time.

In the drawings herewith I have illustrated a preferred embodiment of the invention and in Fig. 1 is shown a front elevation of a telephone showing my attachment thereon.

Figs. 2 and 3 are side and top views respectively of a bracket which may be clamped to the stand of the telephone.

Figs. 4 and 5 are side and plan views, respectively, of the bracket which may be secured to the receiver.

Figs. 6 and 7 are side and plan views respectively of a latching bracket which may be connected with the stand of the instrument.

In Fig. 1 I have shown an ordinary type of desk telephone having a body 1, a base 2,

a transmitter 3, and a hook or switch lever 4. The receiver is shown at 5 and is of ordinary construction and having a receiving end 6 and a handle 7 at the end of which is connected the conducting cable 8 passing into the base 2 of the telephone. A cable 9 connects the telephone in the usual circuit.

The receiver 5 is ordinarily hung upon the hook or switch lever 4 and the weight of said receiver holds the switch closed. A spring on the switch lever 4 tends to move the switch into open position. This spring is not shown, being ordinary construction.

To support the receiver I provide a clamping bracket 10 which has a ring 11 at one end made up of two parts hinged at 12 so that the parts may be swung open on the hinge as a pivot. At one side of the ring or band 11 is a laterally projecting arm 13 which is divided longitudinally on the plane 14 including the hinge 12 and the two parts of the divided arm are held together by a set screw 15 or other similar connecting means. This bracket may be placed about the stand 1 with the arm 13 projecting in a direction approximately parallel with the switch lever 4.

Upon the arm 13 thus provided I secure an arm or support 15 which may be of tubular metal construction; said arm being bent to incline upwardly to a point about even with the level of the transmitter 3. The lower end of said arm at 16 is adapted to telescope over the end of the arm 13. A set screw 17 in the lower end of the arm may be tightened against the arm 13, thus holding the two parts together but allowing an adjustment of the arm 15 relative to the bracket which will enable the operator to swing the upper end of the arm 15 into proper position to hold the transmitter 5. Obviously the arm 15 may be of semiflexible construction such as is commonly employed in desk light supports, if desired.

To support the transmitter upon the arm 15 I employ a split sleeve 18, one end of which is adapted to fit about the handle 7 of the transmitter and to be clamped in position thereon. A laterally projecting arm 19 on the sleeve 18 is also split and the two parts

100

secured together by a set screw 20. The band or sleeve 18 will be open at one side, as shown at 20. The arm 19 is of the proper size to fit within the upper end of the tubular arm 15 and it will be seen that the receiver may be raised from the hook and the arm 19 telescoped into the upper end of the arm 15, thus supporting the receiver in the proper position and the receiver may be pivoted about the upper end of the arm 15 into proper position to accommodate the user.

It is contemplated that the receiver 5 may be supported more or less permanently on the arm 15 and when this is desired I provide a latch to operate the switch 4. This latch is made up of a band 21, which is fitted about the stand 1 of the instrument, said band being hinged at 22. There is a laterally extending arm 23 which is longitudinally divided, and adapted to be held together by means of the set screw 24. The arm 23 may be rectangular in cross section and along the plane of division between the two sections of the arm I form a slot or opening 25. Said slot is in the shape of an inverted U, thus providing a tongue or key 26 with a constricted passage 27 adjacent thereto.

Where the receiver is positioned as shown in Fig. 1 it will throw the center of gravity 30 of the device within the base 2, but if the receiver is moved farther away, some brace or some extension on the base may be employed to prevent tipping of the assembled structure.

I employ in this slot 25 a latch member 28. Said latch has a ring 29 at the lower end to receive the finger of the operator. The body of the latch is of comparatively thin sheet metal and has a longitudinal slot 30 therein, 40 which extends downwardly to a point 31 spaced from the lower end thereof. The upper end of the latch has a hook 35 which may be engaged over the switch lever 4 of the telephone.

With particular reference to Fig. 1, it will be seen that I may adjust the band 21 upon the telephone post 1, to the proper distance below the switch arm 4. In this position the hook 35 of the latch will engage over the arm 4 and the latch may be pulled down until the lower end 34 of the latch engages around the lower portion of the tongue or key 26 on the arm 23, and will thus latch the switch in closed position. When it is desired to release 55 the switch the lower end 29 of the latch will be moved laterally to disengage the shoulder 34 at the lower end of the slot from the tongue or key 26 and the resiliency of the switch arm will throw the switch into open position.

It will be seen that I may leave the receiver 60 permanently on the arm 15. However, if it is desired the receiver may be used without the latch and in that case the receiver may be mounted on the hook or switch arm 4 in the usual manner and when it is desired to use the

telephone the receiver will be removed from the hook and supported on the arm 15 during the telephone conversation. At the close of the period of use of the telephone the receiver may be again hung upon the hook in the usual 70 manner.

My device is simple and economical to construct and is easily adjustable to accommodate any user of the telephone. It will be seen that the arm 15 may be swung about the arm 13 on the telephone post to any desired position and also that the receiver may be pivoted about the upper end of the arm 15 into any desired position. These two adjustments make it possible to place the receiver 75 exactly in a position where it may be left permanently, it thereafter being only necessary to release or close the switch 4 as previously described. The advantages of this construction will be obvious to those skilled in the art. 80

What I claim as new is:

1. A telephone attachment including an arm secured to the telephone body and adapted to support the receiver in adjusted position spaced from said body, a latch to engage and hold the telephone receiver hook depressed, an arm on said telephone body, and a handle on said latch whereby said latch may be released from said arm. 90

2. The combination with a telephone including a body, a switch arm, and a receiver, of a support other than said switch arm for said receiver, a latch hook adapted to engage said switch arm, and an arm attached to said body including means to receive and hold said latch hook downwardly to depress said switch arm. 95

3. The combination with a telephone including a body, a switch arm, and a receiver, of a support for said receiver, comprising an adjustable member, a post pivotally supported therein and means to secure said post to said receiver, a latch hook adapted to engage said switch arm, and releasable means to receive and hold said latch hook downwardly to depress said arm. 105

4. A telephone including a telephone body, a switch arm, and a receiver, in combination with a support adjustable to mount said receiver in a plurality of positions, a latch whereby said switch arm may be held depressed when said receiver is removed therefrom, said latch being manually operative and independent of said receiver support to release said switch arm as desired, and an arm on said telephone body comprising means to hold said latch. 115

5. A telephone including a telephone body, a switch arm, and a receiver, in combination with a support adjustable on said body to mount said receiver in a plurality of positions, a latch hook to engage said switch arm, means to move said latch downward, and means to be engaged with said latch and hold 120

it releasably and the switch arm in lowered position.

6. A telephone attachment whereby the receiver may be held in an operative position including an adjustable support for the telephone receiver, a latching mechanism for the telephone receiver hook comprising an arm arranged for attachment to the telephone body, a latch to engage the receiver hook, and means of connecting said arm and latch.

10 In testimony whereof I hereunto affix my signature this 31st day of December, A. D. 1929.

JOHN R. ELLIS.
